UNITED STATES PATENT OFFICE.

HEINRICH POETTER, OF DUSSELDORF, GERMANY.

BLOWING SYSTEM FOR FURNACES.

1,141,652.

Specification of Letters Patent. Patented June 1, 1915.

Application filed May 8, 1914. Serial No. 837,210.

To all whom it may concern:

Be it known that I, HEINRICH POETTER, a subject of the King of Prussia, residing at 126 Grafenbenger Allee, Dusseldorf, Germany, have invented certain new and useful Improvements in Blowing Systems for Furnaces, of which the following is a specification, reference being had to the accompanying drawings.

10 This invention relates to a method of and apparatus for the working of furnace installations and more especially of gas generators, by means of which a steam jet air injector is automatically put in operation immediately the fan of the blowing device, from any cause, is thrown out of action. By this means explosions in the air spaces of the generators due to the backward flow of the gas into the air space are prevented, 20 while moreover explosions in the gas pipes themselves due to the fact that, when the blowing device is stationary, atmospheric air may be drawn into the pipes through the cooling of the gas are likewise prevented.

25 The construction of the blowing device is such that when started again, the steam jet injector is automatically again put out of action, an arrangement which considerably facilitates the change from one method of 30 working to the other, hitherto by no means free from danger, and entirely does away with all possibility of danger to the attendants operating the generators and furnaces.

An arrangement in accordance with this 35 invention is illustrated in the accompanying drawings, wherein—

Figures 1 and 2 illustrate alternative arrangements of apparatus, the various valves being shown in section.

40 The arrangement shown in Fig. 1 comprises a double valve for the steam supply pipe, consisting of a pair of suitably adjusted valves *a* and *b* which are almost completely balanced or relieved from pressure.

45 The valve *a* permits of the flow of steam through the pipe *c* to the air space of the generator. The steam thus added to the air supply from the blowing device may be styled additional steam and will flow 50 through the valve *a* and the pipe *c* so long as the blowing device is in operation, while the valve *b* through which the steam jet injector is supplied, remains closed. The valves *a* and *b* are controlled by means of two bells *d* and *e*, which work in cisterns *d*, *d*,

containing liquid, connected by means of pipes *f* and *g* respectively with the air supply pipe *h* of the blower and with the air supply pipe *i* of the steam jet injector. The bells *d* *e* are suspended by links *d*₂, *e*₂ from the arms *d*₃, *e*₃ of a lever carried by a shaft *d*₄ and on this shaft there is also secured a lever *d*₅ from the extremities of which the valves *a* *b* are suspended. So long, therefore, as the pressure in these air supply pipes exceeds the maximum gas pressure of the furnace plant, the bell *d* will remain in the position shown in the drawing, and consequently the valve *a* will remain open and the valve *b* closed. An adjustable weight *k* 60 is provided on the arm *d*₃, by means of which the operation of the bells can be suitably regulated in accordance with the working conditions. When now from any cause whatever, such for instance as the failure of the electro-motor *l* due to short-circuiting, the failure of the coupling *m* or the like, the pressure beneath the bell *d* falls this bell, on account of the fact that its weight exceeds that of the bell *e*, will be forced into its 65 lowest position, with the result that the steam jet injector *i* will immediately become operative through the opening of the valve *b*, whereby the flap valve *n* will be reversed through the lateral air pressure exerted from the direction of the injector, so that the sliding surface at *o* is moved beyond the aperture at *p*. To facilitate the rapid action of the flap valve, it is important that the bell should be raised by the blast from the injector into its highest position, before the flap valve *n* has been rotated beyond its central position, so that the valve *b* may be 70 promptly opened and the full pressure may be exerted on the valve *n*. As soon as the flap valve *n* has been moved beyond its central position, a suitably arranged counter-weight *q* turns it into its extreme position 75 whereupon the blast from the steam jet injector can flow freely through the aperture *p* into the air space of the generator. As soon as the blowing device again begins to act, while the steam jet injector is still operative, the air passing through the blowing device will force the bell *d* upward, this being due to the fact that the pipe *h* is still closed by the flap *n*. The steam jet injector, however, will immediately be rendered inoperative by the closing of the valve *b* with the result that the flap valve *n* will at the 80 85 90 95 100 105 110

same instant be caused to move into its initial position in the manner already described.

In some instances, as shown in Fig. 2, 5 there may be substituted for the two bells *d* and *e* an electro-magnet *r* so connected with the circuit of the electro-motor *l* of the blowing device that so long as the magnet receives current, its armature *s* is drawn in 10 and the valve *a* is opened and consequently the valve *b* closed, while upon the failure of the current supply and the consequent stoppage of the motor, the magnet becomes de-energized, and its armature *s* falls under 15 the action of the counterweight *k*, thereby closing the valve *a*, opening the valve *b*, and causing the flap valve *n* to be actuated in the manner and with the result already described. The reversal of the movement and 20 of the action of the valves can also be effected without any trouble whatever, as the magnet, as soon as it is again supplied with current, attracts its armature and consequently renders the steam jet injector inop- 25 erative while the normal air pressure is again supplied by the blowing device.

From the foregoing description it will be obvious that apparatus in accordance with this invention may easily be applied to en- 30 tire groups of generators having a common blowing device and gas collecting flue.

What I claim is:—

1. In a furnace installation the combination of a blowing device adapted to be 35 driven by power with a second blowing device adapted to be actuated by a steam jet, means whereby, upon the failure of power supply to the first mentioned blowing device, steam can be automatically supplied to 40 the second blowing device, thereby maintaining the blast, and blast pipes leading from said blowing devices to a common blast delivery pipe.

2. In a furnace installation the combination of a blowing device adapted to be 45 driven by power with a second blowing device adapted to be actuated by a steam jet, means whereby, upon the failure of power supply to the first mentioned blowing device, steam can be automatically supplied to 50 the second blowing device thereby maintaining the blast, blast pipes leading from said blowing devices to a common blast delivery pipe and at the junction of said blast pipes 55 and delivery pipe, a flap valve adapted, when subject to excess of pressure in one of the blast pipes to close the passage between the other blast pipe and the delivery pipe.

3. In a furnace installation, the combi-

nation of a blowing device adapted to be 60 driven by power with a second blowing device adapted to be actuated by a steam jet, a valve chamber, a steam pipe communicating therewith, a lever mounted to oscillate within said valve chamber and connected to 65 a shaft extending to the exterior of said chamber, valves carried by the arms of said lever, one of said valves being adapted when unseated to supply steam to the blast from the first mentioned blowing device and the 70 other of them when unseated to supply steam to said jet, seats for said valves within said chamber, a second lever connected to said shaft externally of said chamber, bells carried by the arms of said second lever, 75 cisterns containing liquid, wherein said bells are partially immersed, blast pipes leading from said blowing devices to a common blast delivery pipe, at the junction of said blast pipes and delivery pipe, a flap valve adapt- 80 ed, when subject to excess of pressure in one of the blast pipes, to close the passage between the other blast pipe and the delivery pipe, and pipes connecting said blast pipes with the interiors of said bells above the 85 level of liquid in said cisterns.

4. In a furnace installation, the combination of a blowing device adapted to be 90 driven by power with a second blowing device adapted to be actuated by a steam jet, 95 a valve chamber, a steam pipe communicating therewith, a lever mounted to oscillate within said valve chamber and connected to a shaft extending to the exterior of said chamber, valves carried by the arms of said lever; one of said valves being adapted when unseated to supply steam to the blast from the first mentioned blowing device and the other of them when unseated to supply steam to said jet, seats for said valves within said chamber, a second lever connected to said shaft externally of said chamber, a counter- 100 weight on said second lever, and means adapted to raise said lever and counter- 105 weight when the first mentioned blowing device is operative, but to allow said lever to descend under the action of said weight when the said blowing device is inoperative, the first mentioned lever and the valves carried thereby being thus simultaneously and 110 correspondingly operated.

In testimony whereof I have hereunto affixed my signature in the presence of two witnesses.
